MACHINE FOR SHEARING TWISTED STRANDS OF WOOL, &c.

EDWARD T. C. LUTTON, OF PHILADELPHIA, PENNSYLVANIA.

Letters Patent No. 60,211, dated December 4, 1866.

SPECIFICATION.

TO ALL WHOM IT MAY CONCERN:

Be it known that I, EDWARD T. C. LUTTON, of Philadelphia, Pennsylvania, have invented certain mechanism for Shearing Twisted Strands of Wool and other fibrous material; and I do hereby declare the following to be a full, clear, and exact description of the same, reference being had to the accompanying drawing, and to the letters of reference marked thereon.

My invention consists of knives operating substantially as described hereafter, in combination with certain devices for so guiding and turning twisted strands of fibrous material that the superfluous projecting fibres may be shorn off, an operation which, when applied to coarse American yarn, renders the same equal, as regards smoothness and appearance, to the finest German zephyrs.

In order to enable others to make and use my invention, I will now proceed to describe a mode of carrying it into effect, reference being had to the accompanying drawing, in which—

Figure 1 is a longitudinal section of a machine for shearing twisted strands or threads of wool and other fibrous material.

Figure 2, a transverse section on the line 1-2, fig. 1.

Figure 3, a plan view; and

Figure 4, an enlarged sectional view of the shearing knives.

Similar letters refer to similar parts throughout the several views.

To a suitable table or base, A, is secured a frame, B, from which projects a bracket, D, and in the latter turns a vertical tubular spindle, E, provided at the top with a small pulley, F, and beneath the bracket with a hub, G, from which project four or other desired number of blades, a. To the frame B is secured a stationary knife, d, in such a position that the under surfaces of the blades a shall revolve in close contact with the upper surface of the said knife d, without bearing hard on the same. Both the revolving and the stationary blades are bevelled, and thus reduced to a sharp cutting edge, as illustrated in the enlarged view, fig. 4. To the rear of the frame B is secured a plate, e, having an inclined slot for the ready introduction of the yarn or thread, x, which traverses in a direction parallel, or nearly so, with the edge of the stationary knife, d, and very slightly below the cutting edge of the same, as seen in the enlarged view, fig. 4. The yarn passes upwards through the tubular spindle, E, and through an eye, h, formed by a wire secured to the pulley F, a short distance from the centre of the same, the yarn passing from this eye to a suitable reel round which it is wound. Prior to reaching the guiding-plate e, the yarn passes from an adjacent reel or "swift" round a pin, i, on a cross-bar, H, secured to the base A, and between the rounded top of this bar and the under side of a cup, I, which is loaded with shot or other small heavy particles, and which has a spindle, m, turning in the said cross-bar.

It is well known that the fine German yarn termed "zephyr" has a peculiar silky and smooth finish, which renders it of much greater value for knitting, embroidery, and manufacturing purposes, than the yarn made in this country. This may be attributed, in a great measure, to the quality of the wool used in Germany, the finest Saxony staples being employed in the manufacture of Berlin zephyr, which is also prepared in such a manner that the fibres are laid evenly.

The wool in this country being much inferior in quality to that of the German or Spanish wool, the yarn spun from it is much coarser, owing, for the most part, to the innumerable fibres which project from the twisted strands, and which do not appear so prominently in the German yarn.

I have found that by cutting off these fibres close to the twisted portions or body of comparatively coarse American yarn, the latter may be rendered equal, as regards smoothness and appearance, to the finest Berlin zephyr. This shearing of the yarn is accomplished rapidly and effectually by the above described mechanism. The tubular spindle E is caused to revolve very rapidly while the thread is drawn forward slowly in the course described above. Owing to the position of the eye h, as regards the centre of the tubular spindle, a twist is imparted to the yarn between the eye and the cross-bar H. By this twist three objects are attained: first, the yarn is turned round so that every part of it is subjected to the action of the knives; second, the twisting has tendency to condense and stiffen the yarn as it passes within the range of the revolving blades, which remove the projecting fibres only, the twisted and stiffened portions remaining entire; third, the twisting has a tendency to make the superfluous projecting fibres more prominent, and consequently in the best condition to be severed. It should be understood that the twist imparted to the yarn between the eye h and cross-bar H, is but temporary, the strands being restored to their original condition on passing between the said eye and the winding

reel. It is important that a uniform tension should be imparted to the yarn as it passes in front of the knife and this tension should be delicately adjusted to accord with yarn of different qualities or numbers. This tension is imparted by the cup I, the weight of which may be regulated by removing or adding to the contents.

It will be seen on reference to fig. 1, that the upper end of a pin, m' , secured to the frame B, projects into an annular recess in the under side of the hub of the knife. The yarn does not actually bear against this pin, otherwise the latter would interfere with the temporary twisting of the yarn, the pin merely serving as a guard to prevent the body of the yarn from being caught by the knives and severed, which might take place where any irregularity occurs in the yarn. A number of shearing knives with their adjuncts may be arranged on one machine, so that a number of threads may be operated on simultaneously.

Although I have described certain mechanism for shearing yarn, it will be evident that these devices may be altered, modified, and other devices substituted for those described, without departing from the main features of my invention; for instance, a single revolving knife, or a vibrating knife, may be substituted for the rotating blades, or both the upper and lower knives may be made to rotate or vibrate, or a spiral knife may be used, in a manner somewhat similar to that employed in cloth-shearing machines; in all cases, however, the turning of the yarn and the guiding of the same, are essential. I have hitherto alluded to woollen yarn as the material to be shorn, but it will be evident that other twisted fibrous strands, even cordage, may be sheared by mechanism equivalent to that described.

Without confining myself to the specific arrangement, construction, and operation of the devices herein described, I claim as my invention, and desire to secure by Letters Patent—

Knives operating substantially as described, in combination with the devices herein set forth, or their equivalents, for so guiding and turning twisted strands of fibrous material, that the same may be shorn by the said knives.

In testimony whereof I have signed my name to this specification in the presence of two subscribing witnesses.

EDWARD T. C. LUTTON.
